Fig. 8.

A technical line drawing of a mechanical assembly. The main body is a hatched component labeled 36. A slot 35 is cut into its upper surface. A circular part 37 is attached to the side of the body. A small circular component 38 is positioned within the slot 35. A hatched part 39 is attached to the top of the body. A slot 40 is cut into the top surface of part 39. A long, thin, hatched part 34 extends from the side of the body. The entire assembly is labeled 'Fig. 11.'

C. L. Parker Attorney

UNITED STATES PATENT OFFICE.

SAMUEL R. SEESE, OF VANDERBILT, PENNSYLVANIA.

PERMUTATION-SWITCH.

1,338,099.

Specification of Letters Patent. Patented Apr. 27, 1920.

Application filed April 29, 1919. Serial No. 293,509.

To all whom it may concern:

Be it known that I, SAMUEL R. SEESE, a citizen of the United States, residing at Vanderbilt, in the county of Fayette and State of Pennsylvania, have invented certain new and useful Improvements in Permutation-Switches, of which the following is a specification.

My invention relates to a permutation switch adapted to be installed upon automobiles or the engine thereof to prevent the unauthorized operation of the automobile.

An important object of the invention is to provide a device of the above-mentioned character, which is formed of few and simple parts, and which may be easily and conveniently operated when the combination is known.

A further object of the invention is to provide a device of the above-mentioned character which may be easily operated for opening and closing the circuit, if desired, without working the complete combination.

Other objects and advantages of the invention will be apparent during the course of the following description.

In the accompanying drawings forming a part of this specification and in which like numerals are employed to designate like parts throughout the same:

Figure 1 is an elevation of the front face of the device;

Fig. 2 is a side elevation of the device;

Fig. 3 is a central vertical longitudinal sectional view through the same;

Fig. 4 is a transverse sectional view, taken on line 4—4 of Fig. 3;

Fig. 5 is a detail transverse section, taken on line 5—5 of Fig. 4;

Fig. 6 is a perspective view of the operating shaft or rod;

Fig. 7 is a detail section through the same, showing the way in which the inner and outer parts thereof are connected and insulated;

Fig. 8 is a transverse sectional view, taken on line 8—8 of Fig. 3;

Fig. 9 is a perspective view of the control rack, showing one of the stationary con-

Fig. 10 is a perspective view of a leaf spring; and,

Fig. 11 is a perspective view of the contact arms.

In the drawings, wherein for the purpose 55 of illustration is shown a preferred embodiment of my invention, the numeral 10 designates a casing, fitted within an opening 11, formed in a dash 12. This casing is provided at one end with a flange 13, adapted 60 to engage with a dial 14, these parts being held together by screws 15, passing through the dash 12 and preferably having their heads arranged at the rear of this dash.

Arranged within the casing 10 is a circular support 16, which is formed of insulated material. This support is secured to the casing 10 by screws 17 or the like.

Upon the forward side of the insulated support 16 is arranged an annular control 70 member or rack 18, crimped for providing depressions or notches 19. This annular control member comprises stationary contact elements 20 and 20' thoroughly insulated from the other portions of the control 75 member. These stationary contacts are connected with binding posts or screws 21, connected with wires 22, included in the ignition circuit, one of these wires passing through an opening 23. The rear end of 80 the casing 10 is closed, as shown at 24, and this closed end is equipped with a tube 25, which may receive one wire 22. The stationary contacts 20 and 20' are arranged opposite each other, as shown in Fig. 4. 85

The numeral 21' designates an operating shaft or element, formed in sections 22' and 23', which are rigidly connected and thoroughly insulated from each other. As shown in Fig. 7, the section 22' is provided 90 with a longitudinal groove 24', while the section 23' carries an extension or tongue 25', projecting into this groove. Screws 25' engage with portions of the section 22' and pass through openings 26, insulating material 27 being arranged between the sections 22' and 23' and within the openings 26, as shown. The forward section 22' is equipped with an annular shoulder 28, and forwardly of the shoulder is a portion 29, 95 100

which is square in cross section. Forwardly of the square portion 29 is a reduced portion 30, circular in cross section, and carrying a head 31, separated therefrom and 5 clamped thereto by a set screw 32. The circular portion 30 is slidably mounted within an opening 33 formed in the insulating support 16.

The numerals 34 and 35 designate contact 10 arms, the outer ends of which carry curved elements 36, to fit in the notches or depressions 19. The stationary contact elements 20 and 20' forming in effect a continuation of the control member 18, prevent the combination from being ascertained by the 15 travel of the contact arms over the control member. The contact arm 34 is provided at its inner end with a head 37, having a circular opening 38 formed therein, rotatably receiving the square portion 29, whereby this contact arm is rotatable upon the square portion. The contact arm 35 is provided at its inner end with a head 39 provided with a square opening 40 receiving 20 the square portion 29, whereby the contact arm 35 is locked to the shaft 21 for rotation therewith. At their inner ends the contact arms 34 and 35 are provided with angularly arranged spaced shoulders 41 and 25 42, adapted to be moved into and out of contact with each other, as shown. The numeral 42' designates a leaf spring, which is secured to the central portion of the support 16 by screws 43', and the free end of 30 this spring is slotted, as shown at 44', to receive the circular portion 30, and to engage beneath the head 31.

The dial 14 is provided with an annular scale 43, shown in Fig. 1, and a pointer 44 40 is adapted to travel in proximity to this scale. This pointer is secured to a radially extending handle or knob 45 carried by the shaft 22', and serves to turn the same. The pointer 44 and the contact arm 35 extend in 45 the same direction and remain parallel.

The point *a* on the scale 43 indicates the 50 location of the stationary contact 20, and the point *b* the location of the stationary contact element 20', while these contact elements 55 may be arranged in other positions. The points *c* and *d* indicate the extent of travel of the contact arm 35 with relation to the contact arm 34, moving in either direction when said contact arm 34 is in engagement 60 with the contact element 20. To close the switch the pointer 44 is first shifted to the point *b* which would bring the contact arm 35 into engagement with the contact segment 20', and then the pointer is advanced to the point *d*, which is necessary to advance 65 the contact arm 34 into engagement with the stationary contact arm 20. The contact arm 35 now disengages the contact element 20' and the pointer is swung into an opposite

direction so that it is returned to the point *b* 65 whereby the contact arm 35 engages the contact element 20'. The circuit will now be closed as is obvious. If it should be desired to open the circuit without working the entire combination to again close it, the contact arm 35 may be swung in either direction from the point *b* between the points *c* and *d*. When the shaft 22' is rotated, the spring 42' will normally hold the contact arms 34 and 35 in proper engagement with 70 the control member 18 but will permit of slight reciprocatory movements of the shaft to allow the contact arms to trip over the control member.

It is to be understood that the form of my 80 invention herewith shown and described is to be taken as the preferred example of the same, and that various changes in the shape, size and arrangement of parts may be resorted to without departing from the spirit of 85 the invention or the scope of the subjoined claims.

Having thus described my invention, I claim:

1. A permutation switch of the character 90 described, comprising a support, an annular control member carried by the support and provided with notches and including insulated contact elements, contact arms arranged to travel in proximity to the control member and to engage with the same, spaced shoulders carried by the inner ends of the contact arms, an element connected with one arm to turn it so that the shoulder of such arm engages the shoulder of the other contact arm to advance the other contact arm, and means for indicating the extent of 95 movement of the arms.

2. A permutation switch of the character 100 described, comprising a support, a curved control member carried by the support and provided with notches and including spaced insulated stationary contacts, contact arms arranged to travel in proximity to the curved control member to engage the same, means whereby one contact arm may be swung a restricted distance with relation to the other contact arm and will then serve to swing such other contact arm, means to turn 105 the first named contact arm, and means for 110 indicating the extent of movement of the first named contact arm.

3. A permutation switch of the character 115 described, comprising a support, a curved control member carried by the support and 120 provided with notches and including spaced insulated stationary contacts, a contact arm to travel in engagement with the control member and provided at its inner end with an opening which is polygonal in cross section, a coacting contact arm to engage the control member and provided at its inner end with an opening which is circular in cross 125

section, an operating shaft pivotally connected with the support and provided with a portion which is polygonal in cross section, such portion passing through the 5 polygonal and circular openings of the contact arms, shoulders carried by the inner portions of the contact arms and normally spaced, a dial having a scale, and a pointer

connected with the operating shaft and traveling in proximity to the scale. 10

In testimony whereof I affix my signature in presence of two witnesses.

SAMUEL R. SEESE.
